MILK SAFE

Irving Berger, New York, N. Y.

Application October 19, 1939, Serial No. 300,150

1 Claim. (Cl. 232—42)

This invention relates generally to receptacles and more particularly to milk-safes or receptacles for the keeping of milk or other articles of a similar nature.

Among the objects of the present invention is the provision of structure adapted to act as a deposit and collection receptacle for use with all manner of articles which may be delivered at the home or office or taken therefrom when the place is unattended, yet will prevent unauthorized tampering or theft.

Another object herein lies in the provision of a novel receptacle which may be used as a convenient carrier to transport the delivered articles from the threshold to some other point, as for example to the refrigerator in the dwelling.

A further object of the present invention lies in the provision of novel mounting structure cooperating with the new receptacle so that the receptacle is readily put in place and automatically locked by a simple single operation.

A feature of the present construction permits the receptacle to be readily unlatched by the proper person even when the receptacle is fully loaded.

Another feature of this invention lies in the fact that there is substantially only one moving part, and this is adequately concealed and protected so that picking or tampering are discouraged and prevented; no hinged parts or moving doors on the receptacle being utilized.

Another object of the present invention lies in the novel construction of the receptacle and the mounting structure therefor, wherein the channel member for cooperation with the mounting structure is formed integrally with the receptacle and is fabricated at the same time. In accordance with the present invention, the receptacle and the mounting structure are preferably formed up from sheet metal stock. The invention thus by reason of novel design and organization of the various parts permits economical large scale production with consequent wide distribution. Large door delivery service organizations such as dairies, and bakeries will find the present receptacle and mounting highly desirable since the low cost thereof may be paid from the saving in goods, the theft of which is prevented.

These objects and other incidental ends and advantages will more fully appear in the progress of this disclosure and be pointed out in the appended claims.

In the accompanying drawing forming a material part of this disclosure, similar reference

characters designate corresponding parts throughout the several views, in which:

Figure 1 is a view in perspective as seen from the outside of the building, or outside of the door, showing the receptacle in engagement with the mounting means or structure.

Figure 2 is a view in elevation as seen from the inside of the building, or inside of the doorway, showing the receptacle in engagement with the mounting means, and the door swung partially open through 90 degrees.

Figure 3 is an elevational view showing the receptacle in engagement with the mounting means, as seen from the "outside" side or wall thereof.

Figure 4 is an elevational view showing the receptacle in engagement with the mounting means, as seen from the "inside" wall or side thereof. This figure is a rear view of Figure 3.

Figure 5 is a horizontal sectional view (enlarged) of Figure 4 as seen from the plane 5—5 thereon.

Figure 6 is an enlarged sectional view showing in detail the lower right hand corner portion 25 of Figure 5.

Figure 7 is an end elevational view of the receptacle, that is to say the end containing the latching mechanism, the right hand end in Figure 5. In this figure the handle member is broken away, and the scale is reduced from Figures 3 and 4.

Figure 8 is an elevational view of the mounting structure, as seen from the left in Figure 5. The scale is the same as Figure 7.

Figure 9 is a fragmentary view in perspective (enlarged) showing in detail the upper left hand corner of the mounting structure as shown in Figure 8.

The receptacle generally indicated by numeral 40 10 comprises a bottom 11, a top 12, an inside or front wall 13, an outside or rear wall 14, a curved end wall 15, a channelled end wall 16, and a handle member 17. The front wall 13 is provided with an aperture 18 having an indentation 19 facilitating manual access to the handle element 31. The bottom 11 and the top 12 are substantially identical in size and configuration and are secured in any suitable manner, for example by soldering, to the lower and upper edges respectively of the single metal sheet generally indicated by numeral 20. The sheet 20 is suitably folded and formed to have the several portions which are the front wall 13, the curved wall 15, the rear wall 14, the channels 21 and 22 which are integral with the end wall 16. The handle

member 17 is suitably affixed to the top 12 at the points 23 and 24, as for example by soldering.

The manner in which the sheet 20 is folded and formed is best seen in Figures 5 and 6 of the accompanying drawing. In accordance with the present construction the single sheet 20 begins at one edge of the aperture 18 with the portion 43 and extends completely around the receptacle 10 to terminate with the portion 44 at the other edge of the aperture 18. This construction permits economies in manufacture and results in a strong seamless wall. The indentation 19 may be of any suitable configuration to permit ready and convenient access to the handle element 37. While the wall 13 is shown having an aperture 18 of such size that the wall is in effect divided into wall portions 43 and 44, it will, of course, be obvious to those skilled in the art to which the present invention pertains, that such aperture may be made of any size suitable to allow the passage therethrough of the articles for which the receptacle 10 is to be used. Since the channels 21 and 22 are substantially identical but oppositely directed, a detailed description of one will suffice for both. From the starting point at the extreme left the inside or front wall continues to the right as seen in Figure 5, and this wall 13 makes a right angle bend at 25 outwardly. Continuing outwardly another right angle bend 26 is made so that the sheet material now travels toward the curved end 15 to the 180 degree bend 27. Continuing toward the wall 16 the sheet 20 makes a right angle bend 28 so that it travels inwardly of the receptacle 10 thus forming the wall 16. The wall 13 is of course provided with the complementary bends 29 and 30 so that the channel 21 is offset inwardly with relation to the receptacle 10; while the wall 14 is similarly provided with the complementary bends 31 and 32 so that the channel 22 is inwardly offset.

The inward offset of the channel 21 allows the receptacle 10 to be placed close to the door 81 so that the wall 13 may be flush therewith when the receptacle 10 is locked within the mounting structure or means generally indicated by numeral 82. The inward offset of the channel 22 permits the mounting means to be narrower than the receptacle 10 with a corresponding reduction in weight and cost.

The lower portion of the channelled end wall 16 is provided with a rectangular orifice 33 to permit the latching element 34 to oscillate about the pivot formed by the rivet pin 35 mounted in and projecting vertically upwardly from the bottom 11. The latching element 34 is substantially V-shaped having the forward end thereof suitably rounded and beveled as is well known in the art to permit the said element to cooperate with the latching plate 36 on the mounting means 32. The latching plate 36 has the upper portion thereof curved toward the inner surface of the body 47. The inner end of the latching member is provided with a vertically upwardly projecting integral handle element 37. The latching element 34 is maintained in operative position by means of a contractile coil spring 38. Spring 38 resiliently connects arm 39 of the latching element 34 by penetrating an orifice 40 in arm 39 with pin 41 on bottom 11. A stop 42 mounted upon the bottom 11 serves to limit the forward movement of the latching element 34, while rearward movement of the latching element 34 is limited by the abutment of the arm 39 against the inner surface of the wall 13 adjacent thereto.

Turning now to the mounting structure or

means generally indicated by numeral 82, this is preferably formed from a single sheet of material which is formed by bending same into shape. This construction permits the use of lighter material with consequent reduction in cost of material and in cost of manufacturing. The mounting means is provided with two oppositely disposed channels 45 and 46, the configuration of which is best seen in Fig. 6 of the accompanying drawing in which one of the channels, namely, 45, is shown. Since the channels are complementary and substantially identical, a description of one will suffice for both. As seen in Figure 6, the body 47 of the mounting means has a plurality of right angle bends 48, 49 and 50 resulting in the channel 45 which is of substantially U-shaped formation having the open portion of the U facing toward the inner surface of the body 47.

In Figure 9, the channel 46 is shown having corresponding right angle bends 48', 49', and 50'. The upper portions of both of the channel members 45 and 46 are cut away to form angularly and downwardly directed entrance edges 51 and 52 including portions 53, 54, 55 and 56. The purpose of the entrance edges 51 and 52 is to facilitate the rapid and convenient insertion of the lower corners 57 and 58 respectively of the channels 21 and 22.

The lower edge of the body 47 of the mounting means 82 is provided with a tab of metal which is bent inwardly and upwardly upon itself to form a latching plate 36 substantially semi-circular in vertical section which thus has the upper portion thereof curved toward the inner surface of the body 47. The latching plate 36 is adequately secured at the upper edge thereof to the inner surface of the body 47 by means of the flange 59, (see Figure 5) which is soldered to the said body. The latching plate 53 is provided with a suitable orifice 60 adapted to receive and engage the latching element 34.

The mounting structure or means is provided with a plurality of suitable orifices 61 which may be utilized for the penetration of screws or other devices to secure the mounting means 32 to the door jamb 62.

While the spacing of the channels 21, 22, and 45 and 46 with relation to each other has been slightly exaggerated in Figures 5 and 6, this has been for the purpose of clarity in the drawing and it will be understood that only sufficient clearance should be allowed between the parts to permit the same to rest and slide within one another. Obviously, the device may be given any desired protective coating such as paint or enamel, or the same may be made of a non-corroding metal.

Operation

The mounting means 82 is secured to the door jamb 62 by means of screws (not shown) through the holes 61 with the lower edge thereof resting on the step 66. The mounting means 82 may be fastened to either of the door jambs and it is found more convenient to place it on the one near the hinged edge of the door. The receptacle 10 is preferably kept during the daytime near the refrigerator within the dwelling and after the milk has been consumed, the bottles 65 are placed within the receptacle 10 through the aperture 18. The receptacle is manually carried by means of the handle 17 to the door step 66 and is rested thereon. The milk man in delivering filled bottles merely removes the empties from the aperture 18 and inserts the filled bot-

ties. Lower corners 57 and 58 of the channels 21 and 22 are placed within the upper portion of the mounting means 32 in contact with the inner surface of the body 47. Since the channels 45 and 46 have been cut away at the upper portion thereof as has been previously described, and since the greatest width of the wall 16 is slightly less than the distance between the entrance edges 51 and 52, this insertion is rapidly and smoothly accomplished. The downwardly and angularly directed portions 53 to 56 inclusive facilitate this operation. The handle member 17 is then lowered and with it, of course, the receptacle 10 until the latching element 34 strikes the upper curved surface of the latching plate 36. The latching element is forced inward by reason of the cam action of the curved surface of the latching plate and as soon as the latching element 34 and the orifice 60 are aligned, the element 34 is pulled outwardly by spring 38 so that the receptacle 10 becomes locked in place. Since the wall portions 43 and 44 are in contact with the lower portion of the door 81, it is impossible to remove the bottles 65 from the container 10 while the door 81 is closed. It is, of course, a simple matter to open the door 81 away from the device 10, which will then appear as seen in Figure 2. A quick manipulation of the handle element 37 will release the latching element 34 and the whole receptacle 10 may be removed by means of the handle 17 and transported with the bottles 65 to the refrigerator or other place.

When the spring 38 is of low tension construction, the latching operation will occur merely by reason of the weight of the receptacle 10 and the bottles 65 pushing downwardly. If desired, however, the spring tension 38 may be increased so that in addition to the weight of the receptacle 10 and the bottle 65, a manual pressure will be required in order to actuate the latching element. In the latter case instead of merely resting the container 10 on the door step 66, the channels 21 and 22 may be inserted within the upper portion of the mounting means 32 and the container 10 will be supported off the surface of the door step 66 by reason the latching element 34 resting on the upper rounded portion of the latching plate 36. The receptacle 10 may then be lifted to remove the empty bottles and may be pushed downwardly to be locked into place with the full bottles therein.

It may thus be seen that I have provided a novel milk safe possessing the several features

of lightness in weight, economical construction, a high degree of convenience and facility yet which is tamper and theftproof.

The foregoing description has been made rather detailed for clearness of understanding only, and no unnecessary limitations should be understood therefrom, but the appended claim should be construed as broadly as permissible in view of the prior art.

10 I claim:

A milk-safe for use with a door and a jamb: said safe having a bottom, a first wall disposed to face the door when the door is closed and a second wall; said first wall having an edged aperture through which bottles may be removed or replaced, said edge having an indentation extending toward said second wall; said second wall being composed of sheet metal having an orifice disposed adjacent said bottom and a pair of oppositely disposed integral channels composed of folds of the sheet metal forming said second wall; said channels being arranged perpendicularly with relation to the bottom of said safe; a latching element pivotally mounted upon 20 said bottom for rotation about a vertical axis; said latching element having an arm and a forward end; a spring resiliently connecting the arm to said bottom and urging the forward end through the orifice in the second wall; said arm having an upwardly extending handle element 25 lying adjacent the said indentation; mounting means composed of sheet metal, adapted to be secured to the jamb and including a latching plate substantially semi-circular in vertical section; the upper portion thereof curving toward the inner surface of the mounting means, said latching plate having a hole; said mounting means having a pair of oppositely disposed second channels integrally bent from the sheet metal of which the mounting means is composed; the second channels being adapted to slidably engage the pair of channels on the second wall whereby the second channels are adapted for 30 vertical rectilinear reciprocation therein; the forward end of the latching element being adapted to rest upon the upper surface of the curved latching plate to support the safe in an unlocked condition and upon downward pressure upon the safe, to engage said hole and thereby stop all 35 sliding movement; said handle being accessible through said indentation whereby the safe may be unlocked while loaded with said bottles.

IRVING BERGER.
